UNITED STATES PATENT OFFICE.

GEORGE W. GARDNER, OF CHICAGO, ILLINOIS.

CLEANER FOR ENGINE-CYLINDERS.

1,080,208.

Specification of Letters Patent.

Patented Dec. 2, 1913.

Application filed October 28, 1912. Serial No. 728,071.

To all whom it may concern:

Be it known that I, GEORGE W. GARDNER, a citizen of the United States of America, residing at Chicago, in the county of Cook and State of Illinois, have invented certain new and useful Improvements in Cleaners for Engine-Cylinders, of which the following is a specification.

This invention relates to improvements in an attachment for gasolene, gas or other hydrocarbon or elastic fluid engines, and it consists in certain peculiarities of the construction, novel arrangement and operation of the various parts thereof, as will be hereinafter more fully set forth and specifically claimed.

The invention has for its principal object to provide automatic, simple and inexpensive means for cleaning or maintaining in a clean condition the cylinder or cylinders of the engine, which means shall be of such construction, arrangement and relation of its parts to the engine as to utilize the pressure and impulsive force of the exhaust or escaping gases to create a strong suction from the engine cylinder or cylinders, whereby the foul and residual gases or unconsumed particles of carbon will be withdrawn therefrom, as well as from the combustion chamber and exhaust cavity, and so that no back pressure in said parts will occur, and the formation of carbon on the walls thereof will be prevented, to the end that a pure carbureted charge will be afforded for each explosion or discharge of the engine.

Another object of the invention is to utilize the impulsive force of the waste gases to muffle or reduce the noise incident to the explosion and exhaust of the engine, by means of a rotary undershot wheel or fan.

Other objects of the invention will be disclosed in the subjoined description and explanation.

In the accompanying drawing which serves to illustrate an embodiment of the invention—Figure 1 is a side view of a portion of the exhaust pipe of an engine, showing a cleaner embodying the invention mounted thereon and illustrating said pipe as being provided with a muffler of the ordinary construction; Fig. 2 is an enlarged plan view partly in section of the cleaner and a portion of the exhaust pipe on which it is mounted, and Fig. 3 is a longitudinal sectional view taken on the line 3—3 of Fig. 2, looking in the direction indicated by the arrows.

Like numerals of reference refer to corresponding parts through the different views of the drawings.

The reference numeral 5, designates a portion of the exhaust pipe of an engine, which pipe may be provided near its free or discharging end with a muffler 6, of the ordinary or any preferred construction.

The cleaner consists of a tube or pipe section 7, which is adapted at each of its ends to engage a section of the exhaust pipe, as is clearly shown in the different views of the drawing, and for this purpose each end of the tube 7, is by preference internally screw threaded to engage external screw threads on the sections 5, of the exhaust pipe, but it is obvious that said tube and sections may be united in other ways. The tube or pipe section 7, is provided with an enlargement 8, which, by preference, is located on the upper surface of said tube and in conjunction therewith form part of a casing for a rotary fan or wheel, which is designated as a whole by the reference numeral 9, and consists of a hub 10, and a series of vanes or arms 11, extended radially from the hub so that in the rotation of the fan or wheel 75 they will approximate the lower inner surface of the tube 7, and the inner surface of the enlargement 8, of the casing. One of the sides of the tubular member 7, and of the enlargement 8, has secured thereto by means of screws 12, a plate 13, which is provided centrally with an internally screw threaded projection 14, in which is located a set screw 15, the inner end of which is pointed or cone-shaped as at 16, to engage a similarly shaped socket 17, in one end of the hub of the fan or wheel, and said screw may be fixed in the desired position by means of a jam-nut 18, mounted on the outer portion thereof. The opposite side of the tubular member 7, and its enlargement 8, has secured thereto by means of screws 12, the flattened end or plate 24, of a by-pass tube or pipe 19, the other end of which is secured to the member 7, and in communication therewith between the enlargement 8, and that end of the tube 7, adjacent to the engine, as will be clearly understood by reference to Fig. 2, of

95

100

105

the drawing. That portion of the tube 19, which is secured to the enlargement 8, is provided with an internally screw threaded projection 20, in which is fitted a set screw

- 5 21, the inner end of which is pointed or cone-shaped as at 16, to fit in a correspondingly shaped opening in that end of the hub of the fan 9, adjacent to the tube 19, to form one of the bearings for said fan. The screw 10 21, also has a jam-nut 18, mounted thereon to fix the same in any desired position. At a point to register or communicate with the forward end of the opening in the pipe 19, the tube 7, is provided with an opening 22, 15 and just rearwardly of said opening with an inwardly and forwardly extended lip or flange 23, which will act as a baffle or guide to assist in diverting the waste gases from the cavity of the tube 7, into the front end 20 of the by-pass opening. The plate or flattened portion 24, of the tube 19, which portion is secured to one side of the tube 7, and enlargement 8, thereon, is provided with a series of openings 25, which communicatively connect the interior of the tube 7, and enlargement 8, with the cavity of said pipe and form the discharge opening therefor. The outer end of each of the vanes or arms 11, of the rotary fan is preferably enlarged 25 as at 26, and are extended in the opposite direction from that in which the fan rotates when in operation.

One side of the fan or wheel casing, usually the side plate 13, is provided with an opening for access to the interior of said casing, so that the fan or wheel may be reached with the finger to test the ease or difficulty of its rotation. This opening is normally closed by a cover 27, which may be secured in place by screws 28, or otherwise. The ease with which the fan 9, can be rotated is regulated by tightening or loosening the set or bearing screws 15, and 21, which rotatably support the fan or wheel 45 at the ends of the hub.

From the foregoing and by reference to the drawing, it will be understood that the exhaust pipe 5, may be communicatively connected to the engine in the ordinary or 50 any desired way, and that the impulse action of the exhausted gases therethrough being intermittent and the motion of the fan or wheel being continuous and at a high rate of speed, it and the by-pass will act 55 as a pump to clear the cavities of the engine of residual gases, thus keeping them clean and preventing overheating of the cylinders, thereby requiring less water for cooling purposes and increasing the general efficiency 60 of the engine. Moreover, the rotatable fan will break up the volume of exhaust gases and muffle the noise thereof, and force said gases through the muffler, when the same is used, with such force as to thoroughly clean 65 the same and keep it in such condition.

Having thus fully described my invention, what I claim as new and desire to secure by Letters Patent is—

1. In a device of the character described, the combination with a conduit, of a casing communicating therewith and having a by-pass leading therefrom to said conduit, and a vane-wheel or fan rotatably mounted in said casing. 70

2. The combination with an exhaust conduit of an engine, of a casing communicating therewith and having a by-pass communicating at one of its ends with said conduit in front of the casing and at its other end with said casing, and a vane-wheel or fan 80 rotatably mounted in the casing. 75

3. The combination with an exhaust conduit of an engine, of a casing communicating therewith and having a by-pass communicating at one of its ends with said conduit in front of the casing and at its other end with said casing inwardly of the periphery 85 thereof, and a vane-wheel or fan rotatably mounted in the casing. 80

4. The combination with an exhaust conduit of an engine, of a casing communicating therewith and having a by-pass communicating at one of its ends with said conduit in front of the casing and at its other end with said casing by means of a plurality of 90 openings, and a vane-wheel or fan rotatably mounted in the casing. 90

5. The combination with an exhaust conduit of an engine, of a casing communicating therewith and having in its front portion an opening, a lip or flange secured on the inner surface of the casing rearwardly of said opening and extended inwardly and forwardly thereof, a by-pass conduit communicating at one of its ends with said 100 opening and at its other end with said casing, and a vane-wheel or fan rotatably mounted in the casing. 100

6. The combination with an exhaust conduit of an engine, of a casing communicating therewith and having a by-pass leading therefrom to said conduit, a baffle located rearwardly and inwardly of the front end of said by-pass, and a vane-wheel or fan 110 rotatably mounted in the casing. 110

7. The combination with an exhaust conduit of an engine, of a casing having side walls and a partly circular cavity in communication with said conduit, a by-pass conduit in continuous communication at one of 120 its ends with said exhaust conduit in front of the casing and at its other end with said casing through a plurality of openings in one of the sides thereof, and a vane-wheel or fan rotatably mounted within the casing. 115 125

8. The combination with an exhaust conduit of an engine, of a casing having side walls and a partly circular cavity in communication with said conduit, an adjustable bearing in each of the walls of the casing, a 130

vane-wheel or fan rotatably mounted within the casing on said adjustable bearings, a bypass conduit in continuous communication at one of its ends with the exhaust conduit in front of the casing and at its other end with said casing through a plurality of openings located in one of the side walls around the adjustable bearing therein.

In witness whereof, I have hereunto subscribed my name this 25th day of October 10 1912, in the presence of two subscribing witnesses.

GEORGE W. GARDNER.
